UNITED STATES PATENT OFFICE.

WILLIAM C. SKINNER, OF ROCHESTER, NEW YORK, ASSIGNOR OF ONE-HALF TO WILLIAM H. BURNS, OF ROCHESTER, NEW YORK.

COMBINED HAY AND STOCK RACK.

No. 895,119.

Specification of Letters Patent.

Patented Aug. 4, 1908.

Application filed July 23, 1907. Serial No. 385,122.

To all whom it may concern:

Be it known that I, WILLIAM C. SKINNER, of Rochester, in the county of Monroe and State of New York, have invented a new and useful Improvement in a Combined Hay and Stock Rack, which improvement is fully set forth in the following specification and shown in the accompanying drawings.

This invention relates to certain new and useful improvements in combined hay and stock racks designed to be attached to an ordinary wagon body.

It has for its objects among others to provide an improved simple attachment of this nature embodying standards or brackets with screw threaded shanks designed to be secured vertically at the opposite sides of the wagon body and peculiarly constructed and adapted to hold movable arms having trunnion portions at their inner ends occupying openings in the upper expanded portions of the standards or brackets, and serving, when in vertical position, as the sides of a stock rack for carrying small animals, such as calves or sheep, and when in their nearly-horizontal position adapting the wagon for use as a hay rack, the said arms being connected together upon each side of the wagon body by longitudinal bars or strips. The construction of the standards and arms is such that the latter cannot be detached from the standards when the arms are in a vertical position, nor when they are in their lowermost or nearly horizontal position, but the arms must be turned to an angle of substantially forty-five degrees from a perpendicular, when they can be readily passed obliquely upward out of the slots or openings in the expanded parts of the standards or brackets. In some instances the standards may be formed with ears or lugs by which they may be secured to the sides of the wagon body.

Other objects and advantages of the invention will hereinafter appear and the novel features thereof will be specifically defined by the appended claims.

The invention, in its preferred form, is clearly illustrated in the accompanying drawings, which, with the numerals of reference marked thereon, form a part of this specification, and in which

Figure 1 is an end view of a wagon body with my improvement applied. Fig. 2 is a

detail in side elevation with the same fitted to serve as a stock rack. Fig. 3 is an enlarged detail in elevation of the standard and its coöperating arm. Fig. 4 is a view taken at right angles to Fig. 3. Fig. 5 is a detail in elevation showing the position the parts must assume before the arm can be detached from the slot or opening in its standard. Fig. 6 is a sectional detail more particularly hereinafter referred to.

Like numerals of reference indicate like parts throughout the several views.

Referring to the drawings 1 designates a wagon body, of known construction, except as hereinafter specified. 2 are cross bars arranged beneath the bottom thereof.

As the standards and arms are all alike, a description of one thereof will suffice. As seen best in Fig. 3 the standard 3 has a screw threaded shank 4 which is designed to pass freely through an opening in one of the cross bars 2 as seen in Figs. 1 and 2, there receiving a nut 5 engaging beneath said cross bar for holding the parts relatively in the position shown. The upper end of the standard is expanded as shown at 6 at opposite edges as seen best in Fig. 4, and in each of these expanded portions there is formed an opening of peculiar shape and which serves an important function in conjunction with the arm soon to be described. This opening 7 has a rounded lower wall 8 from the front of which extends the upward slot 9 open at its upper end and disposed at an angle of about forty-five degrees from a perpendicular. At the inner end of the opening is a shoulder 10 at the front side of which is the inclined surface 11 substantially parallel with the lower wall of the slot 9 as seen clearly in Figs. 3 and 5. From this inclined surface 11 extends the vertical wall 12 and then the horizontal shoulder 13 the front wall of which is inclined as seen at 14 parallel with the lower wall of the inclined slot 9 as seen best in Figs. 3 and 5.

The standard is preferably formed at its upper end with the ears or lugs 15 as seen best in Fig. 4 for the reception of suitable means as the screws 16 as seen in Fig. 2 whereby the standards may be secured to the sides of the wagon body. The standard 105 may further be provided with a hole 17 as seen in Fig. 4 for the reception of additional securing means 18, as seen in Fig. 2. As

many of these standards as may be found necessary may be employed upon each side of the wagon body.

19 is an arm which may be of any suitable length and contour in cross section. At its inner end it is provided with the trunnions 20 substantially semi-circular in form as seen best in Fig. 5, and of a thickness to just pass through the slot 9 between the inclined surfaces 11 and 14 and the inclined front wall of said slot when the arm is turned in the proper relation, which is that indicated in Fig. 5. The web 21 gives strength to the arm and serves to form a bearing for the trunnions 15 and to take a portion of the strain thereon when in use. As many of these arms as may be found necessary are employed for the one wagon body and those on each side are connected by the longitudinal bars or strips 22 20 as seen in Figs. 1 and 2.

In use, when the bars or arms 19 are in the position in which they are seen in Fig. 2, and in Fig. 1 in dotted lines they, with their longitudinal strips, constitute the sides of a stock rack, and when in this position they cannot be removed from their engagement with the standards owing to the fact that their trunnions engage the vertical wall 12 and the horizontal shoulder 13 as seen best in Fig. 6, and when the said arms are in their nearly horizontal position as seen in Fig. 3 by full lines and in Fig. 1 by full lines the arms cannot be disengaged from the standards because the trunnions rest in the curved portions of the openings in the expanded portions of the standards and their inner upper surfaces engage the horizontal shoulder 10 as seen by full lines in Fig. 3:

In order to take the strain from the shoulders 10 when the arms are in their horizontal position I provide the standard with an abutment or the like 23 between the side portions 40 6 at the upper end as seen in Fig. 6 and against the under side of which the upper 45 surface of the flat or horizontal portion 24 of the arm engages to the rear of its trunnion. This further tends to prevent disengagement of the arm from the standard until the former has been brought into the oblique position in 50 which it is seen in Fig. 5.

The rack may be held in its vertical position in any suitable manner, as for example by suitable means as the hooks 25 on the end gate 26.

55 What is claimed as new is:—

1. A standard for the purpose described having a screw-threaded shank at its lower end, and at its upper end an extended part at its opposite edges with an opening in each 60 extended part, each opening having a rounded bottom with a shoulder extending over the rear upper end of each rounded bottom with a parallel-sided inclined slot leading upward from each opening.

65 2. A standard for the purpose described

having a screw-threaded shank at its lower end, and at its upper end an extended part at its opposite edges with an opening in each extended part, each opening having a rounded bottom with a shoulder extending over the rear upper end of each rounded bottom with a parallel-sided inclined slot leading upward from each opening and a horizontal shoulder in the rear wall of each of said inclined slots. 75

3. A standard for the purpose described having at its upper end an expanded part with opening having rounded bottom wall, an adjacent horizontal shoulder, and an inclined slot leading outward from said opening combined with an arm having semi-circular trunnions with the flat faces thereof uppermost. 80

4. A standard for the purpose described having at its upper end an expanded part 85 with opening having rounded bottom wall, an adjacent horizontal shoulder, an inclined slot leading outward from said opening, and a second horizontal shoulder upon a different horizontal plane combined with an arm having semi-circular trunnions with the flat faces thereof uppermost. 90

5. A standard for the purpose described having at its upper end an expanded part 95 with opening having rounded bottom wall, an adjacent horizontal shoulder, an inclined slot leading outward from said opening, a second horizontal shoulder upon a different horizontal plane, and a vertical wall between said shoulders combined with an arm having semi-circular trunnions with the flat faces thereof uppermost. 100

6. A standard for the purpose described having at its upper end an expanded part 105 with opening having rounded bottom wall, an adjacent horizontal shoulder, an inclined slot leading outward from said opening, a second horizontal shoulder upon a different horizontal plane, a vertical wall between said shoulders and an inclined surface leading from the uppermost shoulder combined with an arm having semi-circular trunnions with the flat faces thereof uppermost. 110

7. A standard for the purpose described having at its upper end an expanded part 115 with opening having rounded bottom wall, an adjacent horizontal shoulder, an inclined slot leading outward from said opening, a second horizontal shoulder upon a different horizontal plane, a vertical wall between said shoulders, and inclined surfaces leading from the outer walls of said shoulders parallel with the inner front wall of said slot combined with an arm having semi-circular trunnions with the flat faces thereof uppermost. 120

8. A standard for the purpose described having a shank screw-threaded at one end and separated expanded parts at the upper end, said expanded parts each having an 130

opening with rounded lower wall, separated horizontal shoulders and an inclined slot leading from said opening, combined with an arm having trunnions movably mounted in 5 said openings.

9. A standard for the purpose described having a shank screw-threaded at one end and separated expanded parts at the upper end, said expanded parts each having an opening with rounded lower wall, separated horizontal shoulders and an inclined slot leading from said opening, combined with an arm having trunnions movably mounted in 10 said openings and an abutment between said 15 expanded parts against which the end of the arm beyond its trunnions engages when the arm is in its horizontal position.

10. A rack for wagons having side portions consisting each of a series of standards having screw-threaded shanks and secured to a 20 side of the wagon body, the upper ends of

said standards having each separated extended parts with aligned openings therein having rounded bottoms, separated horizontal shoulders and inclined slots leading upwardly therefrom, and an arm carried by each standard and longitudinal bars connecting the arms as a single body, the arms being detachably connected with the standards and having lateral trunnions engageable in 25 said slots and seated in said openings with portions engaging one of said shoulders when the arms are in horizontal position and engaging the other of said shoulders when the arms are in a vertical position.

In witness whereof I have hereunto set my hand this 20th day of July, 1907, in the presence of two subscribing witnesses.

WILLIAM C. SKINNER.
